Primary Examiner — Sandra Snapp(74) Attorney, Agent, or Firm — Leanne Taveggia Farrell; Westman, Champlin & Koehler, P.A.(57) CLAIM

The ornamental design for a picnic table, as shown and described.

DESCRIPTION

FIG. 1 is a perspective view of a picnic table; FIG. 2 is a front view thereof, the back view being identical; FIG. 3 is a left side view thereof, the right side being identical; FIG. 4 is a top view thereof; and, FIG. 5 is a bottom view thereof.

The broken lines shown in the drawings are included for purposes of illustrating portions of the picnic table and form no part of the claimed design.
